UNITED STATES PATENT OFFICE.

ADAM R. EGLIN, OF CHICAGO, ILLINOIS.

HAY-CARRIER.

SPECIFICATION forming part of Letters Patent No. 267,682, dated November 21, 1882.

Application filed September 2, 1882. (No model.)

To all whom it may concern:

Be it known that I, ADAM R. EGLIN, residing at Chicago, in the county of Cook and State of Illinois, and a citizen of the United States, have invented a new and useful Improvement in Hay-Carriers, of which the following is a full description, reference being had to the accompanying drawings, in which—

Figure 1 is a side elevation, showing the carrier mounted on its track or rail; Fig. 2, an end elevation of the carrier, with the track or rail in section; Fig. 3, a detail, being an elevation of one section or side of the frame; Fig. 4, an edge elevation of one section or side of the frame, and Fig. 5 a plan view of the locking-catch.

This invention relates to that class of hay-carriers in which a frame is suspended from a rail or track, on which it is made to travel back and forth to deposit the load where required, and has for its objects to improve the construction and operation of the devices for simultaneously locking the frame or carrier and releasing the elevating head or block and unlocking the frame or carrier and locking the elevating head or block, both of which operations are to be automatically performed, and to improve the construction and operation of the carrier as a whole; and its nature consists in the devices and combinations of devices hereinafter described, and pointed out as new in the claims.

In the drawings, A represents the frame, which may be made of cast-iron or other suitable material, and is made in two sections or halves, each having a corresponding shape, and each formed of an upper cross-bar, a, side bars, a' a'', and center bar, b, having extensions b', one on each side, running to and joined with the lower end of each side bar, as shown in Figs. 1 and 3. The bars b' of each section are connected together by a web, c, of a semi-circular inclined form.

B is a funnel or bell-shaped guide, formed of the webs or walls c, by means of which the interlocking end of the elevating head or block is guided or directed into position to be locked.

C is the latch for locking the frame or carrier and releasing the elevating head or block. This latch may be cast or otherwise formed to have at one end an L-shaped slot, f, and at its other

end an open recess or notch, g. Each side bar a'' of the frame has an enlargement, d, in which is an inclined slot, d', to receive a pin or stud, e, on each side of the latch C, which pins and slots attach the latch to the frame, so that it has a limited rise and fall and forward and backward movement. The other end of the latch C is held in position by a bolt, f', which passes through the slot f, which bolt passes through the center bars, b, of the frame, each bar having a hole, f'', through which the bolt passes. The two halves or sections of the frame are secured together by the bolt f' and two bolts j, one at each lower corner of the frame-pieces, which bolts j pass through suitable openings, j', therefor in the frame-pieces, and the two halves are held against the strain of the bolts by lugs i i' i'', formed on the inner face of the side piece a'' and bottom pieces, b', of one section or half of the frame, which lugs or projections are of the required length to maintain the halves or sections of the frame the distance apart for the location of the latch and the swinging hook which locks the elevating head or block between them.

D is a stop, made of a single piece of metal, bent or otherwise formed in two parts, h h', one of which, h, forms a catch to interlock with the notch or recess g, and the other, h', a means for attaching the stop to the under side of the rail by means of screws or bolts h'', as shown in Fig. 1. This stop is to be located in such relation to the load to be unloaded as to suspend the carrier over such load, and by engagement of the latch C therewith hold the carrier stationary.

E is the elevating head or block, made of cast-iron or other suitable material, and having a depending hook, E', for the attachment of the hay-fork, with its side pieces extended up and joined at their ends to form a hook.

F is the hook on the head or block E, for holding the load suspended from the carrier or frame.

G is a hook suspended from a bolt, k, and of sufficient length to come below the rear end of the latch C, and so located and arranged as to be in engagement with or rest against the rear end of such latch, as shown by the dotted lines in Fig. 1. This hook G, as shown, when at the limit of its outward swing, comes in con-

tact with the stud or projection i'' , and the bolt k , from which it is suspended, is in line, or nearly so, with the center of the hook F on the elevating head or block E , and this bolt passes through tubular projections k' , one on each inner face of the center bars, b , which projections furnish additional bearings for the bolt against the strain of the load when suspended by the hooks F G . The flanges or web c are nearly flush with the inner faces of the rear bars b' , so as to leave an open space for the swing of the hook G , but are extended farther beyond the face of the front bars b' , forming an inclined way, b'' , for engagement with the back of the hook F , so that such hook will pass into the mouth or opening B to a point where the hook G , when disengaged, will swing inward and beneath the acting portion of the hook F , locking the two hooks together.

H is a grooved wheel located in the head or block E , and secured in position by a bolt, m , which forms a journal on which the wheel can revolve.

I is a grooved wheel located in the rear lower corner of the frame A , and mounted on one of the tie-bolts j , which forms a journal on which it can revolve.

J is an elevating-rope, one end of which is secured to the frame by being attached to the bolt j at the lower forward corner of the frame, as shown, or in some other suitable manner. This rope J passes under the pulley-wheel H in the elevating head or block and over the pulley-wheel I on the frame, and thence to the point where the operator stands.

K is a track, made of a piece of wood or other suitable material, and suspended in the usual manner, so that the carriage or carrier can move back and forth thereon.

L represents carrying-wheels, one located at each upper corner of the frame A , and held in position by a suitable bolt, l , so as to be free to revolve on the bolts. These wheels travel on the upper face of the track K , and the frame A is of greater width at the point where the track passes than where the latch and suspending-hook are located.

The operation is as follows: The fork, with the load, is suspended from the hook E' , and is elevated with the head or block E through the rope J in the usual manner, during which operation the carriage or carrier is locked and held stationary by the engagement of the notch g with the catch or stop h , as shown in Fig. 1. The elevation is continued until the hook F passes into the opening or mouth B , strikes against the under face of the latch C at its rear end, throwing the forward end of such hook down, releasing the catch g , and at the same time carrying the latch bodily forward, allowing the suspending-hook G to swing inward beneath the hook F , locking the load to the carriage or carrier, when it can be moved, by pulling on the rope J , over the track K to the point where it is to be deposited, and when deposited the carriage or carrier is returned on

the track K to its normal position. The return movement of the carriage or carrier causes the rear portion of the forward end of the latch to come in contact with the stop h , forcing the latch backward, releasing the hook G from the hook F , so that the head or block E is free to descend, and at the same time this backward movement of the latch, through the travel of the pins or studs e in the inclined slots d , raises the forward end of the latch, so that the stop h enters the notch g , locking the latch, and also the carriage or carrier, and this lock is rendered more permanent by the passage of the bolt f' into the L portion of the slot f , preventing accidental displacement, and also holding the carriage or carrier firmly in position until the next ascent of the head or block E .

By making the frame in two sections or halves each formed of a top piece, a , side pieces, a' a'' , center pieces, b , with continuations b' c , a very light frame is provided, and one possessing the requisite strength and rigidity to do the required work, and by providing the lugs or projections i i' i'' the two sections of the frame can be readily put together without requiring extra work in adjusting them for the location of the latch and the swinging hook.

By arranging the latch and swinging hook as shown and described it will be seen that the operation of one depends upon the successful operation of the other, so that the latch cannot be locked without releasing the hook, and the hook cannot be engaged without releasing the latch, and by suspending the latch through the pins or projections e and bolt f' , with the slots d' and f , it is free to rise and fall at its forward end, and to slide in or out to the limit of the slots, which limit is that required for releasing and engaging the hook G , and by forming the slots as shown the latch will be maintained in its locked position, and at the same time it is readily thrown into position to be unlocked.

The acting end of the hook F is broadened out, so as to project beyond the sides of the main portion and be of greater width than the width of the acting end of the hook G , so that when the two hooks are interlocked the acting end of the hook F will project beyond the sides of the hook G , and these projecting portions of the hook F will strike against the slight flange or projecting portion of the rear bars b' , and prevent the hook from being carried along with the hook G as such hook is forced back by the action of the latch C . Some stop must be provided on the web c or rear bars b' to coact with the hook F , as otherwise there would be no unlocking by the upward movement of the hook G through the latch C , and this stop can be formed in some other suitable manner than by the slight flange on the rear bars b' .

What I claim as new, and desire to secure by Letters Patent, is—

1. The frame or carriage A , composed of two

sections, each constructed of a top piece, *a*, side pieces, *a'* *a''*, center piece, *b*, having the extensions or bars *b'* joining the center and side bars, and provided with the laterally-projecting inclined web or wall *c*, joining the extension or bars, and extended beyond the inner face of one of the latter to form the inclined way or frame *b''*, substantially as described.

2. The frame or carriage *A*, having its forward side portions provided with inclined slots *d'*, in combination with the latch *C*, having at its sides the attached lugs *e*, arranged in the slots of the frame or carriage, and provided at its rear with the slot *f* for suspending it on a bolt, *f'*, substantially as described.

3. The combination, with the frame or carriage *A*, of the vertically-movable and longitudinally-sliding latch *C* and the hook *G*, having its upper end supported at a point above the latch, and adapted to swing on its support, the lower end of the hook normally resting against the rear end of the latch, substantially as described.

4. The combination, with the frame or carriage *A*, of the vertically-movable and longitudinally-sliding latch *C*, the gravitating hook *G*, suspended from its upper end by a support arranged above the latch, on which support the hook can swing, and the elevating-head *E*, having a hook, *F*, adapted to lift the latch and permit the gravitating hook to swing forward, substantially as described.

5. The frame or carriage *A*, composed of two sections, each composed of the top bar, *a*, side bars, *a'* *a''*, center bar, *b*, bottom bars, *b'*, and the laterally-projecting webs or walls joining the bottom bars and extended inward to form the inclined ways *b''*, in combination with the vertically-movable and longitudinally-sliding latch *C* and the hook *G*, suspended at its upper end from a support arranged above the latch, substantially as described.
